Milton Tibbets.

UNITED STATES PATENT OFFICE.

MILTON TIBBETTS, OF DETROIT, MICHIGAN, ASSIGNOR TO PACKARD MOTOR CAR COMPANY, OF DETROIT, MICHIGAN, A CORPORATION OF MICHIGAN.

MOTOR-VEHICLE.

1,335,539.

Specification of Letters Patent. Patented Mar. 30, 1920.

Application filed June 19, 1916. Serial No. 104,460.

To all whom it may concern:

Be it known that I, MILTON TIBBETTS, a citizen of the United States, and resident of Detroit, Wayne county, State of Michigan, have invented certain new and useful Improvements in Motor-Vehicles, of which the following is a specification.

This invention relates to motor vehicles, and particularly to the cooling means for the motor.

One of the objects of the invention is to provide an improved form of radiator construction.

Another object of the invention is to provide an improved form of closing means for the front of a motor vehicle radiator.

Another object of the invention is to form a radiator unit with a front closing means that is effective and is pleasing in appearance.

Another object of the invention is to provide a radiator closing means that will shed mud and water.

Other objects of the invention will appear from the following description taken in connection with the drawings which form a part of this specification, and in which:

Figure 1 is a side elevation and part sectional view of the forward portion of a motor vehicle, embodying this invention;

Fig. 2 is a front elevation of the radiator and associated parts shown in Fig. 1.

Fig. 3 is a horizontal section and partly plan view of the radiator shown in Fig. 1, the shutters being shown in closed position; and

Fig. 4 is an enlarged side elevation of the lower part of the radiator shown in Fig. 1, with parts cut away, and with the shutters in closed position.

Referring to the drawings, 10 represents a water-jacketed motor mounted on the forward part of a motor vehicle and 11 is a hood of any suitable construction which forms a covering for the motor.

The water circulation system for the motor comprises a pump 12 which draws the water from the radiator 13 through a pipe 14, a pipe 15 leading from the pump to the motor water jacket, and a pipe 16 which carries the water from the motor water jacket to the upper part of the radiator 13. A thermostat 17 of approved con-

struction is mounted in a chamber 18 through which the water passes from the pipe 14 to the pump 12. The purpose of this thermostat will be later described.

A fan 19 driven by a belt 20 is mounted at the rear of the radiator 13 for the purpose of increasing the flow of air through said radiator.

The radiator 13 above referred to comprises a core 21 of suitable shape, upper and lower tanks 22 and 23 respectively, and side walls 24. The core 21 may be of any approved form and as shown it is composed of a great many small tubes, each of which is the thickness of the core and is expanded at both ends. These tubes are soldered or otherwise secured together at their expanded ends, thus providing passages 25 for the water as it falls from the upper tank 22 to the lower tank 23. The interior of these tubes form air passages through which the air is drawn by the fan 19 and by the movement of the vehicle. By this arrangement a large cooling surface is provided.

In the operation of a motor vehicle in cold weather, it is frequently desirable to close off the air passages in the radiator either partly or wholly, to permit the motor to warm up more rapidly or to operate at a higher temperature than it would with the radiator fully operative. In the present invention this is accomplished by a radiator closing means mounted in front of the radiator core, and as shown this closing means comprises a series of shutters 26 mounted on horizontal pivots 27, and interconnected by a vertical rod 28 so that they may be operated in unison. In Fig. 1 these shutters are shown in fully open position and it will be seen that in this position they are inclined downwardly from rear to front, being hinged at their lower edges and being limited in movement at their upper edges, thus directing the incoming air toward the passages formed by the tubes of the radiator core. In this inclined position also the shutters will readily shed the mud and water that may be thrown upon them by the wheels of the vehicle.

For the purpose of automatically operating the shutters 26 and opening them as the temperature of the water in the circulation system rises, a connection is provided

between the shutters and the thermostat 17 above referred to. This connection is in the form of a lever 29 having one arm connected by a pin and slot connection 30 with the thermostat and its other arm connected by a rod 31 with an arm 32 secured to one of the shutters 26. In Fig. 1 the thermostat 17 is shown in an expanded state, thus holding the shutters 26 wide open to obtain the maximum cooling effect of the radiator. It will be seen that as the thermostat contracts as the water in the system becomes cooler, it will through the connection above referred to partly or wholly close the shutters 26, and thus diminish the cooling effect of the radiator.

In the radiator unit shown herein there is top wall 33, two side walls 34, and a bottom wall 35 extending forwardly from the front face of the radiator core 21 and forming an inclosure in which the shutters 26 above referred to are mounted. The upper wall 33 is formed by an extended portion of the tank 22, and the lower wall 35 is shown as formed by an extension of the tank 23. Also the side walls 34 are formed by forward extensions of the sides 24 of the radiator. These side walls 34 support the pivots 27 of the shutters 26 and the shutters when closed, as shown in Fig. 4, are flush with the forward edges of said wall. This permits of making the radiator and front closing means in unit form and the unit as a whole presents a pleasing appearance. Also by thus extending the tanks 22 and 23 forwardly they are given greater capacity without presenting a bulky appearance.

Other forms may be made without departing from the spirit or scope of the invention.

Having thus described my invention, what I claim and desire to secure by Letters Patent is:—

1. In a motor vehicle, in combination, a water jacketed motor and a water circulation system therefor, comprising a radiator having its outer walls extending forwardly beyond the front face of the radiator core, movable shutters mounted in the space formed by the wall extensions, a thermostat, and a connection from the thermostat to operate the shutters.

2. In a motor vehicle, in combination, a water jacketed motor and a water circulation system therefor, comprising a radiator having its outer side, top and bottom walls extending forwardly beyond the front of the radiator core, movable shutters mounted adjacent the forward edges of the walls in the space formed by the wall extensions, a thermostat in the circulation system, and an operative connection from the thermostat to the shutters.

3. The combination with a radiator, of a closing means arranged in front thereof and

so mounted as to be downwardly inclined from rear to front when in fully open position.

4. The combination with a radiator, of a closing means comprising movable shutters mounted to be downwardly inclined from rear to front when in fully open position.

5. The combination with a radiator of closing means for the front of said radiator comprising shutters having horizontal pivots at their lower edges, means for swinging said shutters rearwardly to open the same and means for limiting said shutters in such movement to a position above the horizontal plane of the pivots.

6. A radiator unit comprising a core, and having walls extending forwardly from the outer edge of the core and forming an inclosure in front of the face of said core, and movable shutters adapted to close the front face of the inclosure flush with the forward edges of said walls.

7. A radiator unit comprising a core, walls integral with the body of the unit and extending forwardly beyond the outer edge of the core and forming an inclosure in front of the face of said core and shutters pivoted in said walls and adapted to close substantially flush with the forward edge thereof.

8. A radiator unit comprising a core, and having walls integral with the body of the unit extending forwardly from the outer edge of said core and forming an inclosure in front of the face of said core, and shutters pivoted in said walls adapted to close flush with the forward edges thereof and when open to direct the air toward said core.

9. A radiator unit comprising a core, upper and lower tanks having parts extending forwardly beyond the front face of said core, side walls of the core also extending beyond the front face thereof, and closing means for the core mounted in the inclosure formed by the extended parts of said tanks and side walls.

10. A radiator unit comprising a core, upper and lower tanks having parts extending forwardly beyond the front face of said core, side walls also extending beyond the front face of said core, and shutters mounted in said side walls and adapted to close the front face of said core.

11. A radiator unit comprising a core, upper and lower tanks having parts extending forwardly beyond the front face of said core, side walls also extending beyond the front face of said core, shutters mounted in the inclosure formed by the extended parts of said tanks and side walls and means to operate said shutters.

12. A radiator unit comprising a core, upper and lower tanks having parts extending forwardly beyond the front face of said core, side walls also extending beyond the front

- face of said core, shutters mounted in the inclosure formed by the extended parts of said tanks and side walls, and means to automatically operate said shutters.
- 5 13. A radiator unit comprising a core, upper and lower tanks having parts extending forwardly beyond the front face of said core, side walls also extending beyond the front face of said core, pivoted shutters mounted 10 in the extended parts of said side walls and adapted in one position to close the front face of the core, and means to operate said shutters to open and close said core.
14. A radiator unit comprising a core, 15 side walls for said core integral with the body of the unit and extending beyond the forward face of the core, and closing means for the forward face of the core mounted between the extended parts of said walls.
- 20 15. A radiator unit comprising a core, surrounding walls for said core integral with the body of the unit and extending for- wardly beyond the front face of said core, and closing means for said core mounted in the inclosure formed by the extended 25 parts of said walls.
16. A radiator unit comprising an upper tank and a lower tank, a radiator core between the tanks and of less thickness than the tanks whereby the tanks extend beyond 30 one face of the core, and closing means for one face of said core mounted between the extended parts of the tanks.
17. A radiator unit comprising an upper tank and a lower tank, a radiator core between the tanks and of less thickness than the tanks whereby the tanks extend beyond 35 one face of the core, side walls also extending beyond one face of the core, and closing means for the face of the radiator core beyond 40 which said tanks and walls extend.

In testimony whereof I affix my signature.

MILTON TIBBETTS.
